ATTORNEY

UNITED STATES PATENT OFFICE

CHARLES LOFMAN, OF LOS ANGELES, CALIFORNIA, ASSIGNOR TO ROBERTI BROS., A CORPORATION OF CALIFORNIA

ROLL-AROUND BED

Application filed April 12, 1927. Serial No. 183,051.

It will be understood from the above title that my invention relates to a bed organization comprising a bed frame or spring-carrying frame which is intended to stand in a closet or recess, when not in use, and to be moved out, upon wheels included in said organization, to any desired position, before the bed frame is lowered to a position of use,—substantially horizontal.

10 The mentioned bed frame being pivoted to a truck serving as a base, it is a primary object of this invention to provide improved means for automatically enlarging said base, or for bracing the truck frame to which the 15 spring-carrying frame is pivoted; and this I prefer to accomplish by means comprising an arm or a pair of arms on said truck. The mentioned arm or arms may be pivotally movable, in a horizontal plane, by means such 20 as a cam or cams on the mentioned bed frame, to obviate danger of an accidental tipping of the bed by a hasty or careless attempt to lower said bed frame into the horizontal position of use.

25 Other objects of my invention will be brought out in the following description of one particular embodiment thereof, and in the accompanying claims, taken in connection with the drawings, in which

30 Fig. 1 may be regarded as a top plan view of the carriage or truck of my recess bed, posts comprising the bed frame being broken away, and an outer position of one of a pair of brace arms being shown by dot-and-dash lines,—no attempt having been made in these drawings to indicate mattress-supporting springs or a mattress.

Fig. 2 is a perspective view of the left hand portion of parts shown in Fig. 1—parts of the 40 frame-supporting truck being broken away.

Fig. 3 is a side elevation of the frame-supporting truck, taken from the direction of the arrow 3, in Fig. 1.

45 Referring to the details of the illustrated embodiment of my invention, 11 may be a rigid truck, supported by castors 12 at each of the four corners thereof,—said truck comprising a substantially horizontal frame consisting of two equally long horizontal elements 13, 13' connected by shorter horizontal

end elements 14, 14', and by two intermediate stress members 15, 15'. Said truck organization also comprises an inverted U-shaped or over-arching member intended to have the appearance of and to be equivalent to an ordinary head-board (including any desired intermediate members, not shown). 55

The described truck may also comprise suitably shaped inclined or other pivot posts 16, 16' secured to the frame elements 13, 13',— 60 and vertical or other reinforcing elements 17 may extend between said pivot posts 16, 16' and the end frame elements 14, 14'.

As shown in the drawings, one or both of the horizontally movable base-enlarging 65 brace arms 18 and 18' may be pivoted (as, at 19) to the intermediate stress members 15, 15', in such a way as to provide levers. The outer ends of these levers may carry rollers; and the inner and shorter ends may be so 70 formed as to adapt them to be moved in a horizontal plane by any suitable means. I may secure thereon or shape the same to constitute cams CA, CA', engageable by suitable cam fingers—such as fingers 21, 21' mounted 75 on a spring-carrying frame F, assumed to be pivotally hung, in a known manner (as, by pins 22) on the posts 16, 16'.

The cam fingers 21, 21' are so shaped as to force the arms 18, 18' from a position of disuse (shown in the drawings in full lines) to an outer position,—in which they are intended to obviate risk of tipping the entire organization during a lowering of the bed spring frame from the vertical to the horizontal position; and it will be understood that the cam fingers 20, 20' engage the opposite (or rearward) sides of the cam levers CA, CA', to return them to their retracted positions when the bed frame, pivoting on pins 22, is 80 manually returned to its vertical position of disuse,—in preparation to being replaced in a closet or recess. 85

The lever or levers 18, 18' are intended to be resiliently held in either or both of their 90 mentioned (expanded and/or contracted) positions by resilient means such as springs 23, 23',—one end of each of said springs being shown as attached to a post or a fixed hook or like element 24, 24', projecting 95 100

downwardly from a frame member 14, 14'; and the movable ends of said springs may be respectively attached to posts or hooks 25, 25', or to like elements in or on the arms 18, 18',—said posts or hooks being mounted in off-center positions to adapt the springs 23, 23' to assist the cams 20, 20' in moving the arms 18, 18' and also resiliently to hold said arms in one or the other of their extreme positions.

It being one of the primary objects of my invention to insure a positive engagement of elements such as rollers 26, 26', shown on the outer ends of the respective arms 18, 18', 15 with the floor whenever said arms are extended, and regardless of any minor irregularity in the floor surface, and, on the other hand, to assure easy rolling and guiding of the bed truck, by causing the rollers to be 20 removed from engagement with the floor surface when the arms are in their inner or retracted positions, I may provide means such as a central cam bracket 27, comprising lifting cam fingers 28, 28', adapted to raise the 25 respective arms 18, 18' out of engagement with the floor surface whenever same are resiliently pulled against the upwardly inclined surfaces or edges C, C', of said cams.

Upon the upper surfaces of the arms 18, 30 18' are respectively mounted truck-steadying organizations 29, 29' comprising brackets 30, 30' and lever rods 31, 31', extending through central openings in said brackets and suitably bent at both projecting ends, to operate 35 in a manner which I will next describe.

Referring to either or both of said frame-lifting organizations, an inner and longer bent end 32 of the rod 31 is intended, when the opposite end 33 lies flat, to project slightly upward,—adapting end 32 to come into contact with the member 15; but the (outer and shorter) bent end 33 of the rod 32 is intended to lie flat upon the surface of the arm 18, in a position adapting it to pass under the frame member 13' only while the arm 18 occupies an inner position or swings outwardly, and previous to the time of contact between the finger 32 and member 15. When the mentioned finger 32 is forced, by engagement with 15 (or 15') and under tension of the spring 23, into a vertical position, the shorter bent end 33 (at such time in a position under the forward frame element 13') is tilted into an upwardly projecting position, relative to the horizontal surface of the arm 18, thereby pressing upwardly against the frame member 13' carrying the rollers 12, and/or exerting a corresponding downward pressure upon the roller 26, carried by 60 the arm 18.

The cam fingers 21, 21' are unequal and spaced apart; paired parts are symmetrical; and it will be understood that the "snap" action of the tension springs 23, 23' (incipiently to a completion of either of the de-

scribed movements) is effective not only to vary the elevation of the floor-engaging members 26, 26' but to swing the cams CA, CA' from positions of engagement by fingers 20, 20' into positions of engagement by 70 fingers 21, 21', or vice versa.

I emphasize the simplicity and reliability of the mode of operation of a bed of the type above described, any desired trundling of the truck 11 being effected in a usual manner while the spring-carrying frame F remains upright, and an enlargement of base and steadyng of said truck being quickly and easily accomplished, in an automatic manner, by simply pulling the upper end of 80 the spring-carrying frame forwardly and downwardly,—the danger of tipping of the whole organization being obviated by the advance of the above-described base-enlarging levers, shown as respectively provided 85 with truck-steadying organizations 29, 29'; and ease of rolling and guiding is assured by the automatic lifting of the base-enlarging arms off the floor when said arms are returned to retracted positions.

It should be understood that, although only one particular embodiment of my invention has been above described, various parts thereof might be independently used; and I am aware that various changes might 95 be made by those skilled in the art, without departure from the spirit and scope of my invention, as the same is indicated above and in the following claims.

I claim as my invention:

1. In a roll-around bed organization comprising a truck to which a bed frame is pivoted: a base-enlarging arm pivotally mounted on said truck and provided with a floor-engaging member; means comprising oppositely disposed cam fingers mounted on said bed frame and adapted to engage said arm for rendering a tilting of said bed frame effective to shift said arm in a horizontal plane between an inner position and an outer position; and separate means mounted upon said arm and engageable with a truck member, rendering operation of said last-mentioned means incidentally effective to vary the elevation of said floor-engaging member.

2. In a roll-around bed organization comprising a truck to which a bed frame is pivoted: a base-enlarging arm pivotally mounted on said truck and provided with a floor-engaging member; means comprising oppositely disposed cam fingers mounted on said bed frame and adapted to engage said arm for rendering a tilting of said bed frame effective to shift said arm in a horizontal plane between an inner position and an outer position; and separate means mounted upon said arm and engageable with a truck member, rendering operation of said last-mentioned means incidentally effective to vary the 130

elevation of said floor-engaging member, a plurality of said arms and associated parts being symmetrically disposed.

3. In a roll-around bed organization comprising a truck to which a bed frame is pivoted: a base-enlarging arm pivotally mounted on said truck and provided with a floor-engaging member; means comprising oppositely disposed cam fingers mounted on said bed frame and adapted to engage said arm for rendering a tilting of said bed frame effective to shift said arm in a horizontal plane between an inner position and an outer position; and separate means mounted upon said arm and engageable with a truck member, rendering operation of said last-mentioned means incidentally effective to vary the elevation of said floor-engaging member,—said arm being provided with a “snap-action” spring tending to complete a shifting movement thereof.

4. In a roll-around bed organization comprising a truck to which a bed frame is pivoted: a base-enlarging arm pivotally mounted on said truck and provided with a floor-engaging member; means associated with said bed frame and adapted to engage said arm for rendering a tilting of said bed frame effective to shift said arm in a horizontal plane between an inner position and an outer position; and means rendering operation of said last-mentioned means incidentally effective to lift said floor-engaging member at the completion of an inward movement of said arm, said last mentioned means comprising a centrally-disposed cam bracket.

5. In a roll-around bed organization comprising a truck to which a bed frame is pivoted: a base-enlarging arm pivotally mounted on said truck and provided with a floor-engaging member; means comprising oppositely disposed cam fingers mounted on said bed frame and adapted to engage said arm for rendering a tilting of said bed frame effective to shift said arm in a horizontal plane between an inner position and an outer position; and separate means mounted upon said arm and engageable with a truck member, rendering operation of said last-mentioned means incidentally effective to depress said floor-engaging member at the completion of an outward movement of said arm.

6. In a roll-around bed organization comprising a truck to which a bed frame is pivoted: a base-enlarging arm pivotally mounted on said truck and provided with a floor-engaging member; means associated with said bed frame and adapted to engage said arm for rendering a tilting of said bed frame effective to shift said arm in a horizontal plane between an inner position and an outer position; and means rendering operation of said last-mentioned means incidentally effective to depress said floor-engaging member at the

completion of an outward movement of said arm and by engagement of means on said arm with a stress member of said truck.

7. In a roll-around bed organization comprising a truck to which a bed frame is pivoted: a base-enlarging arm pivotally mounted on said truck and provided with a floor-engaging member; means associated with said bed frame and adapted to engage said arm for rendering a tilting of said bed frame effective to shift said arm in a horizontal plane between an inner position and an outer position; and means rendering operation of said last-mentioned means incidentally effective for a truck-steadying effect,—said truck-steadying means comprising a lever element pivoted on said arm and upwardly movable into engagement with an intermediate member comprised in said truck.

In testimony whereof, I have hereunto set my hand at Los Angeles, California, this 5 day of April, 1927.

CHARLES LOFMAN.
